BOX SHELTERED THIRD RAIL AND SHOE

Charles V. Richey, Jamaica, N. Y., assignor to
Richey Special Third Rail Corporation, New
York, N. Y.

Application September 30, 1936, Serial No. 103,372

5 Claims. (Cl. 191—30)

This invention relates to an improvement in the "third-rail" and shoe of an electric railway system, in which the current for propelling the cars is supplied to the cars through suitable contacts or shoes in sliding contact with the rail.

The main object of the invention is to improve the construction of the rail itself and also to improve the housing for the rail, so as to provide an effective method of guarding it from the effects of weather and the accumulations of snow and ice, and also to prevent contact with the conducting part of the rail by persons or animals crossing or using the car track.

A further object of the invention is to provide a box shelter third-rail constructed in such manner as to permit a broken shoe to drop therefrom.

Still another object of the invention is to provide a contact shoe for use in third-rail systems, adapted to prevent arcing and burning of the shoe when passing over uneven face surfaces on the third-rail, or over rail joints or other bumps on the rail.

Other objects of the invention will become apparent as the detailed description thereof proceeds.

In the drawing:

Figure 1 is a vertical cross section of one form of my improved third-rail and the protective housing connected thereto;

Figure 2 is a fragmentary side elevation of a third-rail shown in Figure 1, parts thereof being broken away to illustrate details of construction;

Figure 3 is a fragmentary plan of a contact shoe forming part of the present invention;

Figure 4 is a vertical transverse section of a modified form of third-rail;

Figure 5 is a vertical transverse section of another modification of said invention; and

Figure 6 is a vertical transverse section of still another form of the invention.

As shown in Figures 1, 2 and 3 of the drawing, the invention comprises a conducting or third-rail 7, shaped throughout its length as a segment of a cylinder. A web 8 projects radially from the main body of the rail 7; and a contact face 9 is formed on the main body, preferably at an angle of 45° to the horizontal when the rail is in proper position, to make contact with the fingers 10, 11 and 12 of a contact shoe 13 extending from the railroad car.

The entire surface of the rail 7, except the inclined face 9, is covered with a sheet of insulation 14. A protecting housing 15 extends around the greater part of the rail 7 and terminates in

a flat part 16 which is substantially parallel to the face 9 when the rail is in operative position. The cover is supported in operative position by means of brackets 17 (only one of which is shown in the drawing) which are shaped to conform to the shape of the rail 7 and its coverings. The lower part of the bracket 17 extends around the web 8 of the rail 7 and seats in a U-shaped recess 18 formed in a bracket 19 having flanges extending in opposite directions therefrom to seat on an insulated block 20 in common use in third-rail systems.

The blocks 20 are provided with apertures 21 adapted to receive dowels 22 extending from the bottom of the bracket 19. The protective cover 15 may be of wood or other suitable insulating material; and is adapted to be secured in position by means of lag screws 23 extending through the bracket 17.

The rail forming the subject matter of the present application is intended to replace the exposed rail now in common use. In order to facilitate the change from the old to the new system, it is essential that the shoe 13 may be used on the old rail R, as indicated in dotted line in Figure 1, until the new rail is completely installed and in order that traffic may not be interrupted during the change from the old to the new system.

The fingers 10, 11 and 12 form an extension of and are pivotally connected to the free end of the contact shoe 13; and springs 24 are arranged at the joints between the shoe 13 and the contact fingers to cause said fingers to bear yieldingly against the inclined face 9 of the new third-rail. This arrangement of the spring contact fingers will compensate for any up and down or lateral movement of the truck carrying the shoe; and since there are three such fingers it is obvious that one of them, at least, will always be in contact with the rail 7, so as to prevent sparking or burning of the shoe.

It will be apparent from Figure 1 of the drawing that if the shoe 13 or any of the fingers supported thereby should become broken, the broken part will fall at once from contact with the third-rail. This will eliminate any possibility of danger which would result from the jamming of a broken shoe or any part thereof in a box sheltered third-rail.

The form of the invention illustrated in Figure 4 differs from that shown in Figure 5, only in the bracket for supporting the housing 15 in position on the third-rail. The bracket 25 in this case comprises a cylindrical portion 26 conforming to the shape of the third-rail and the coverings 55

therefor. Lag screws 27 secure the portion 26 to the cover 15. A strap 28 extends radially from the lower end of the cylindrical portion 26 of each bracket; and terminates in a flange 29 adapted 5 to be suitably secured to the insulated block 20. This bracket construction serves to brace the third-rail against any lateral thrust resulting from the pressure of the shoe fingers on the inclined contact face.

10 In the form of the invention shown in Figure 5, the third-rail 30 is substantially cylindrical throughout the greater part of its cross-sectional area. A web 31 extends radially therefrom; and a groove 32 is formed in the main body diametrically opposite to the web 31. A sheet of insulation 33 is suitably secured to the rail 30 and covers the entire surface of said rail except the inclined contact face 34. A cover of wood or other suitable insulating material 35 is shaped to 15 provide a tongue 36 extending into the groove 32 or the part thereof covered by the sheet 33. A cylindrical portion extends from the tongue 36 around part of the rail 30, and an inclined portion 37 is formed as a part of said cover parallel 20 to the inclined face 34 of the rail 30. The web 31 with its covering 33 seats in a suitable bracket 38 adapted to be secured as usual to the insulated blocks 20.

30 The form of the invention illustrated in Figure 6 is the reverse of that shown in Figure 5. In this case, the bracket 39 for supporting the rail on the insulated block, comprises a base having a tongue 40 extending therefrom to seat in the groove 41 formed radially in the insulated 35 third-rail 42. The upper part of the rail 42 is provided with a tongue 43 adapted to receive the correspondingly grooved part 44 of the protecting hood or cover 45. The hood 45 is provided with an inclined part 46 which is spaced apart 40 parallel to the inclined face 47 of the rail 42 when the parts are properly assembled in operative position.

45 In the forms of the invention illustrated herein the webs on the third-rails constitute stiffening ribs which make the whole structure rigid. In the forms of the invention illustrated in Figures 5 and 6, rails with grooves at both top and bottom would be better for the purpose of insulation. However, this construction would weaken the rails 50 unduly. Therefore, I prefer the form in which a stiffening rib or web is used.

55 It is to be understood that the invention is not to be considered as limited to the specific construction and arrangement described herein, since it is evident that many changes may be made without departing from the scope of the invention as defined by the claims appended hereto.

What I claim is:

1. In an electric railway system, a third-rail suitably supported on the track and having a contact face inclined upwardly and outwardly with respect to the track, an arm extending from 5 a car of said system toward said rail adapted to engage a second third rail, a contact finger pivoted to the end of said arm, and means for holding said contact finger in yielding contact with said inclined face.

10 2. In an electric railway system, a third-rail suitably supported on the track and having a contact face inclined upwardly and outwardly with respect to the track, an arm extending from 15 a car of said system toward said rail adapted to engage a second third rail, a plurality of contact fingers pivoted to the end of said arm and lying normally in contact with said inclined face, and means for forcing said fingers into yielding contact with said face.

20 3. In an electric railway system, a third-rail suitably supported on the track thereof and having a contact face inclined upwardly and outwardly with respect to the track, a covering of insulating material supported by said third-rail 25 and spaced apart substantially parallel to said inclined face, a shoe extending from a car of said system toward said rail adapted to engage a second third rail, and a contact finger pivoted to the end of said shoe and extending into the space 30 between said inclined face and covering, and means for forcing said finger into yielding contact with said inclined face.

35 4. In an electric railway system, a third-rail suitably supported on the track thereof, and having a contact face inclined upwardly and outwardly with respect to the track, an arm extending from a car of said system toward said rail adapted to engage a second third rail, a plurality of contact fingers pivoted to the end of 40 said arm, yielding means for holding said fingers independently in yielding contact with said inclined face, and a protecting cover of insulating material extending over said rail and having a part thereof substantially parallel to the inclined 45 face of said rail.

50 5. In an electric railway system, a third-rail suitably supported on the track and having a contact face inclined upwardly and outwardly with respect to the track, a protective cover extending in spaced apart relationship to said inclined face, and an arm adapted to engage a second third rail extending from a truck of said system and having a shoe in yielding contact with 55 said inclined face.

CHARLES V. RICHEY.
